US00D893568S

(12) **United States Design Patent** (10) **Patent No.:** **US D893,568 S**
(45) **Date of Patent:** **** Aug. 18, 2020**

(54) **EXTRUDER CAP**

(71) Applicant: **MakerBot Industries, LLC**, Brooklyn, NY (US)

(72) Inventors: **Michael C. Pappas**, Houston, TX (US); **Vishnu Anantha**, Brooklyn, NY (US)

(73) Assignee: **MakerBot Industries, LLC**, Brooklyn, NY (US)

(**) Term: **15 Years**

(21) Appl. No.: **29/684,141**

(22) Filed: **Mar. 19, 2019**

(51) **LOC (12) Cl.** **15-09**

(52) **U.S. Cl.**

USPC **D15/138**

(57) **CLAIM**

The ornamental design for an extruder cap, as shown and described.

DESCRIPTION

FIG. 1 is a bottom, front perspective view of a design for an extruder cap;

FIG. 2 is a bottom view thereof;

FIG. 3 is a top view thereof;

FIG. 4 is a left side view thereof;

FIG. 5 is a right side view thereof;

FIG. 6 is a front view thereof;

FIG. 7 is a rear view thereof; and,

(Continued)

FIG. 8 is a front, right side perspective view of the extruder cap shown in an environment.
The broken lines depict portions of the extruder cap that form no part of the claimed design.

1 Claim, 8 Drawing Sheets
